UNITED STATES PATENT OFFICE.

HORACE S. RUMSEY, OF ST. LOUIS, MISSOURI.

WATER-CLOSET.

No. 907,409.

Specification of Letters Patent.

Patented Dec. 22, 1908.

Application filed March 14, 1908. Serial No. 421,184.

To all whom it may concern:

Be it known that I, HORACE S. RUMSEY, a citizen of the United States, residing at St. Louis, in the State of Missouri, have invented 5 a new and useful Improvement in Water Closets, of which the following is a specification.

This invention relates to water closets and particularly to that class of water closets, 10 whose flushing tank is not elevated.

The object of the invention is to improve upon those water closets wherein the flushing tank is so combined with the closet bowl and seat and controlling valves that they shall 15 together form an integral mechanism, and one in which the seat shall automatically control the flushing of the closet.

To this end the invention consists in the structure of parts and their combination substantially as shown, described and claimed.

In the accompanying drawings, which form a part of this specification, Figure 1 represents, in vertical medial section, a water closet embodying this invention; and Fig. 2 25 is a horizontal transverse section of said closet taken in the plane indicated by the line 2—2, Fig. 1.

The invention embraces the combination of the flushing tank with any of the well known water closet bowls, whether formed 30 of iron, porcelain or any other material and of whatever internal structure. The drawing, however, represents a bowl and tank as constructed of porcelain and shows the two 35 parts as if molded in one piece. The bowl is indicated at 4, the seat at 5, and the interior of the tank at 6, said tank being formed by an extension of the base 7 of the bowl and an encircling side wall 8 built thereon and 40 made integral at its upper edge with the upper edge of the bowl.

The closet bowl has the usual flushing passages 9, 10 and 11 and outlet 12 and the seat is hinged to the bowl in the usual manner, as 45 indicated at 3. Into the flushing tank 6, a pipe 13 extends to within a short distance from the bottom of the tank, said pipe being sealed at its upper end in the upper wall of the tank. In the present instance such sealing is effected by making the pipe 13 integral 50 with the upper wall. This pipe 13 is for the purpose of leading water into and out of the tank.

To control the filling of the tank and the 55 emptying thereof for flushing purposes, a specially constructed valve casing is used

and may be of substantially the form illustrated, wherein 14 represents a tubular valve casing provided at its ends respectively with plugs 15 and 16 seated upon gaskets, as is usual in making water tight joints. In this valve casing there is located the reciprocating inlet valve 17, with the usual squared or fluted stem, and the reciprocating flushing valve 18, whose stem 19 protrudes through a 60 stuffing box in cap 15. This stem 19 is also prolonged in the opposite direction and enters a depression in the stem of valve 17. Depending from seat 5 is a valve tripping mechanism 20, which has an inclined head 70 adjustably connected, through nut 21, to the base by which it is secured to the seat. The connection of the valve casing to the water supply may be made through a nipple, substantially as indicated at 22. 75

The drawing represents this integral water closet with the parts thereof in their normal position as when in place and ready for use. When the pressure of water is on, the inlet valve 17 is held to its seat as shown and the 80 flushing valve 18 is held off its seat and the seat 5 is held in a slightly elevated position by the engagement of the valve stem 19 with the valve tripping device 20. When the seat is depressed the flushing valve 18 is 85 forced to its seat and, by the engagement of the extension of its stem with the stem of valve 17, the latter is unseated and the water from the main is allowed to enter pipe 13 and pass into tank 6. In doing so, the 90 air in said tank is compressed until its tension equals that of the pressure of the water in the mains. Then when the weight is removed from the seat the valve 17 will take its seat and the valve 18 will be unseated, due in part to the pressure of the air 95 in the tank forcing the water therefrom through pipe 13 into the flushing passages of the bowl, and, in part to the pressure of the water in the mains acting on valve 17 to seat 100 it. The water will continue to flow from the tank through pipe 13 through the flushing passages and out through the outlet of the bowl until the air compressed in the upper part of the tank has reached atmospheric 105 pressure. The parts will then be in the position shown in the drawings and the usual water seal will be left in the bowl and all will so remain until the seat is again occupied.

The invention claimed is:

In an automatically flushing water closet, 110 the combination with the bowl and seat, of a

flushing tank built around the bowl and integral therewith, a horizontal valve casing in the upper edge of the combined walls of the bowl and tank, which casing communicates 5 with the water supply, with the flushing tank, and with the flushing passages of the bowl, a reciprocating springless feed valve situated in the casing between the inlet of the water supply and the opening into the flush-
10 ing tank, a reciprocating springless flushing valve situated in the casing between the open-

ing into the flushing tank and the flushing passages of the bowl, the stem of one of said valves engaging the stem of the other, and tripping mechanism attached to the seat for 15 removing said valves to fill the tank, the reverse movement of the valve being effected by the pressure of the water in the mains.
